EDWARD M. LOCKWOOD, OF PHILADELPHIA, PENNSYLVANIA, ASSIGNOR TO C. R. CARVER COMPANY, OF PHILADELPHIA, PENNSYLVANIA, A CORPORATION OF PENNSYLVANIA.

COUNTERBLOCK FOR PRINTING-PRESSES.

1,127,045.

Specification of Letters Patent.

Patented Feb. 2, 1915.

Application filed July 7, 1914. Serial No. 849,395.

To all whom it may concern:

Be it known that I, EDWARD M. LOCKWOOD, a citizen of the United States, and resident of Philadelphia, county of Philadelphia, and State of Pennsylvania, have invented an Improvement in Counterblocks for Printing-Presses, of which the following is a specification.

This invention relates to printing or embossing presses and more particularly to an improved construction of counter-block therefor, and consists of certain improvements which are fully set forth in the following specification and shown in the accompanying drawings which form a part thereof.

The object of the invention is to provide a counter-block having means for securing thereto a counter-block plate carrying a make-ready, the construction being such that a number of counter-block plates may be used with the same counter-block, and all of said plates being interchangeable and removably attached to the said counter-block.

It has for a further object to provide a means for locating and locking a counter-block plate to the counter-block so that the make-ready carried by the counter-plate is accurately positioned in juxtaposed relation to the adjacent guide.

My invention also comprehends details of construction, which, together with the features above specified, will be better understood by reference to the drawings, in which:—

Figure 1 represents a plan of a counter-block embodying my invention; Fig. 2 represents a side elevation of the same and its adjuncts secured in operative position upon the head of a press; Fig. 3 represents a section on line $x-x$ of Fig. 2.

Similar numerals of reference indicate corresponding parts.

1 designates a counter-block for use in connection with printing presses, preferably of the embossing type, said block being provided with a stem or extension 2 of tapered form adapted to seat within an opening 3 formed in the head 4. In the present instance only the lower end portion of the head 4 is shown, but it will be understood that this is the general type of head used in printing presses and may be either fixed or reciprocable according to requirements.

The extension member 2 as here shown is fixed within the head 4 by means of a set screw 5 as will be readily seen. In order to prevent turning movement of the block with respect to the head I have shown a dowel pin 6 adapted to seat within a suitable opening 7 in the head 4.

8 designates the counter-block gibs of which there are preferably two spaced a suitable distance apart and each provided with a beveled face 9, said gibs being fixed to the counter-block by screws 10 or like fastening means. It will be noted that the beveled faces 9 are inwardly inclined and conform to the inclined faces 11 of the counter-block plate 12, forming retaining guides 70 which hold the latter in operative position upon the counter-block but allow sliding movement of the counter-plate with respect to the counter-block. 13 designates stop members secured by screws 14, or like means, to one side of the counter-block plate 12 and each projecting at one edge so as to form stops which abut the side face of the counter-block 1.

15 designates a thumb screw having threaded engagement with the counter-block and positioned so that the wing of said nut may be turned to a position overlapping the edge of the counter-block plate 12, thus forming a lock to hold the plate in its operative position. 16 designates the make-ready or strip of soft material which is glued or cemented to the face of the counter-block plate in opposed relation to the die 17 which is of course carried by the opposite head not shown.

In the operation of the device it will be understood that the counter-block 1 while being removably carried by the head 4 is normally fixed thereto and remains substantially as a permanent part thereof so that if a change is to be made in the die the counter-block plate may be readily removed by turning the wing nut 15 so that it no longer extends into the path of the plate 100 and the latter may then be drawn out along the slides provided by the retaining guide gibs 8. As soon as one plate is removed a new counter-block plate with its make-ready strip secured thereto is slid into place 105 with the stop members 13 abutting the face of the counter-block, following which the wing nut is turned to lock it in place. In

this manner it will be apparent that the counter-block plate may be readily and easily interchanged and one make-ready substituted for another with but little loss of time and the machine is ready to resume the pressing or printing operation in a minimum of time.

It will now be apparent that I have devised a complete unitary structure wherein the counter-block is provided with removable counter-plates which are interchangeable one with the other so that each die may have a mounted make-ready provided for the particular use of that die while the interchange of one part for another may be made with quickness and corresponding saving of time. It will also be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without

departing from the spirit or scope of the invention.

Having now described my invention, what I claim as new and desire to protect by Letters Patent is:—

In a device of the character stated, a counter-block adapted to be removably secured to the head of a press, a counter block 35 plate for said counter-block, a make-ready fixed to said plate, undercut guide members secured to said counter-block to form guides and supports for said plate, a plurality of stop members fixed to the front portion of 40 said plate and projecting to one side thereof to contact with said counter-block and determine the operative position of said plate, and a locking member having threaded engagement with said counter-block and 45 provided with a lateral extension adapted to be moved into the path of said plate to form a lock and prevent displacement thereof.

In testimony of which invention, I hereunto set my hand.

EDWARD M. LOCKWOOD.
